UNITED STATES PATENT OFFICE

EUGENE PETERSON, OF NEW YORK, N. Y., ASSIGNOR TO WESTERN ELECTRIC COMPANY, INCORPORATED, OF NEW YORK, N. Y., A CORPORATION OF NEW YORK

WAVE MODULATION AND APPLICATION THEREOF

Application filed October 30, 1926. Serial No. 145,113.

This invention relates to signaling, and especially to modulation and demodulation.

According to this invention undesired magnetic coupling between the input circuits 5 of a magnetic modulator is avoided by having the carrier frequency flux and the signal frequency flux at right angles where they are superposed in the magnetic structure of the modulator.

According to another aspect the functions 10 of a demodulator and telephone receiver are combined in a single magnetic device by effecting demodulation in the magnetic core of the device to produce a flux of signal frequency, which flux cooperates with a steady flux to actuate the receiver diaphragm.

Another feature is the transmission of a 15 signaling side frequency of a carrier wave impressed on a modulator, with suppression of the first harmonic of the carrier wave, and transmission of a signal other than that employing the side frequency, by transmission of the first harmonic of the impressed carrier wave.

Other features of the invention are 20 described hereinafter.

Figs. 1 and 2 show curves for facilitating explanation of the invention; Fig. 3 is a 25 diagram of a two-way, multiplex telephone system involving features of the invention which are referred to above; and Fig. 4 is a diagrammatic side elevation of a receiver demodulator structure included in the system of Fig. 3.

The term "modulation" as used herein, 30 relates to distortion of waves, and especially to phenomena which occur when two electric waves, for example, a so-called carrier wave and a so-called modulating wave, are 35 jointly impressed upon a distorting instrumentality.

It is well known that modulation of this 40 kind yields side frequencies made up of various combinations involving the frequencies of the impressed waves. When one of the waves, either the modulating or carrier wave consists of a band of frequencies the side frequencies likewise assume the form of bands.

The number, amplitude, and frequency 45 characteristics of these side bands are func-

tions of the kind and extent of the distortion as measured, for example, by the equation of the characteristic curve which expresses the relation between the amplitude of the input and output quantities.

In present systems, use is made of the "square" characteristic of this curve, that is, the characteristic which makes the equation of the curve approach the form $y=k x^2$, in which x and y are respectively the amplitudes of the input and output quantities. Other terms having other powers of x may, to some extent, be present. Those in other even powers of x will contribute to the effect secured by the square term as will be explained later. On account of this "square" characteristic, modulation yields side band components having frequencies equal respectively to the sum and difference of the frequencies of the modulating and carrier waves. These side bands with or without some of the original carrier constitute a modulated carrier wave from which the modulating component may be reproduced at a receiving station by a similar distortion.

The terms besides the "square" term, if present, in addition to contributing to the effect of the "square" term, as above, produce other side bands in which harmonics of the carrier or modulating frequencies, or both, instead of the fundamental frequencies, occur. These various combination frequency components or side bands are distinguished from each other by what may be called their order, or the number of times the carrier and modulating frequencies, taken together, occur. This distinction is made use of in defining the order of modulation which produces these components. For example, second order modulation produces second order side bands or side bands of the kind usually employed, in which the carrier and modulating frequencies each occurs once, third order of modulation results in third order side bands or side bands in which the first even harmonic of either the carrier or modulating frequency occurs, etc.

Modulation of order higher than the second may be conveniently designated higher order modulation, or high order modulation;

and side bands of higher order than the second may be designated higher order or high order side bands.

- Pronounced higher order side bands can be produced by modulating means which produce, and operate over, a characteristic curve which has one or more pronounced bends. Where it is desirable, as for example for reasons pointed out hereinafter, that odd order side bands be obtained to the exclusion of the even order side bands, the curve should have two symmetrical bends in relatively opposite directions, that is the curve should have opposite symmetry about each of the axes of coordinates through a point on the curve and the operation should occur equally over the curve in both directions from this point about which the curve is symmetrical. If the operation does not occur about the point of symmetry or if the curve lacks symmetry of this kind, even order side bands will be present. In general, for either case the degree of acuteness of the bends indicates proportionally the amplitudes of the side bands.
- Modulation producing pronounced odd order side bands to the substantial exclusion of even order side bands can be effected by subjecting a closed magnetic path designed for saturation at small magnetizing forces to joint magnetizing action of a carrier magnetomotive force wave and a modulating magnetomotive force wave. These magnetomotive forces can be obtained by sending a carrier current and a modulating current through the same or different magnetizing windings for the path. The path can be, for example, a ring shaped core for the winding or windings. The winding or windings, or another winding on the core, can deliver modulated current. The modulator may be regarded as accomplishing its function by varying the flux density of the core, and therefore the impedance or the mutual inductance of the carrier current and side band current windings, as a non-linear function of the modulating current. Such a magnetic core modulator when operating with symmetry about a point on its characteristic curve suppresses, for example, the double carrier frequency as well as the even order side bands, and since it is easy to separate the fundamental carrier frequency from the third order side bands by a band filter, the use of this type of modulator facilitates transmission of a third order side band with suppression of the fundamental and double carrier frequencies, a type of transmission utilized in the system shown in the drawing and described hereinafter.
- If currents of different frequencies p and q are fed into a distorting (modulating) device, there results a complex current in which, as indicated by a mathematical analysis given presently, the frequency of each current component can be represented by the general ex-

pression $m p \pm n q$, in which m and n may have any or all integral values, or zero values, and in which the symbol $\pm$ indicates that the sum, the difference, or both the sum and difference, of the two quantities may be present.

When either of the coefficients m or n has zero value, the frequency defined by this expression is a direct current if the other coefficient is zero. If the other coefficient is not zero, the current component has a frequency p or q , as the case may be, or a harmonic or harmonics thereof. When neither of the coefficients has zero value there are obtained combination-frequency components of current, that is, side frequencies. The order of modulation is conveniently given as the sum of m and n . When both m and n are unity we have the familiar case of second order modulation in which the side frequencies are $p \pm q$. Third order modulation may be correspondingly represented by $2p \pm q$ or $p \pm 2q$. There are accordingly four possible third order side frequencies. If r is a number expressing the order of modulation (that is, a number which is the sum of two numbers) it is evident that there are $r-1$ combinations of integral numbers (other than zero) which add up to equal r , so that, considering both the sum and difference frequencies, there may be a maximum of $2(r-1)$ different side frequencies for each of the respective orders of modulation.

In what follows, it will be assumed that q represents a band of frequencies as, for example, a voice current (the so-called modulating current) and that p represents a fixed carrier frequency having a value greater than the greatest value of q . The expression "side band" will accordingly be used rather than "side frequency". Also, only the side bands in which q occurs but once, that is, those having frequencies $p \pm q$, $2p \pm q$, $3p \pm q$, etc., will be considered, since only by the transmission of side bands of this type can the modulated component be reproduced at the receiver by modulating such side bands with a wave having the frequency of the unmodulated carrier or a harmonic thereof.

In order to show how various multiple order side bands occur and to determine the extent to which they occur, an extension of the method of analysis used in United States patent to Carson, No. 1,449,382, issued March 27, 1923, is given below.

According to that method a statement of the current (or potential) resulting from modulation is obtained by substituting in the general equation of the type $y = ax + bx^2 + cx^3$ values of the simultaneously impressed currents (or potentials). Suppose that the input currents are $P \cos p_1 t$ and $Q \cos q_1 t$, in which p_1 and q_1 equal respectively $2\pi p$ and $2\pi q$, so that x equals $P \cos p_1 t + Q \cos q_1 t$.

(No material change would result if an initial phase angle between the two impressed waves were assumed.)

This value of α should be substituted in the general equation just given. The first term αx yields merely amplified waves of the impressed frequencies p and q . The term bx^2 yields waves of frequencies $2p$, $2q$, and $p \pm q$, as is well known. The second order 10 side bands $p \pm q$ result from the trigonometric expansion of the product $b P Q \cos p_1 t \cos q_1 t$. The harmonic frequencies $2p$ and $2q$ result from trigonometric expansions of, respectively, $b P^2 \cos^2 p_1 t$ and $b Q^2 \cos^2 q_1 t$.

If each of the remaining terms of the general equation are algebraically expanded by the binomial theorem, it will be found that the expanded equation comprises terms in powers of $\cos p_1 t$ and $\cos q_1 t$, and terms which 20 contain the product $\cos p_1 t \cos q_1 t$ as a factor. The first two obviously yield waves whose frequencies are, respectively, harmonics of p and q . The last obviously yields combination frequency waves, that is, side bands.

Considering these terms which produce combination frequency waves it will be found that alternate terms beginning with the second in the expansion of even power terms of the general equation are of this type and are 30 further characterized in that the exponents of $\cos p_1 t$ and $\cos q_1 t$ are each odd. These terms in their regular order, up to and including the expansion of the sixth power term of the general equation, are as follows, 35 only those coefficients which are necessary in this discussion being retained:

$$\begin{aligned} &PQ \cos p_1 t \cos q_1 t \\ &P^3 Q \cos^3 p_1 t \cos q_1 t \\ &PQ^3 \cos p_1 t \cos^3 q_1 t \\ &P^5 Q \cos^5 p_1 t \cos q_1 t \\ &P^3 Q^3 \cos^3 p_1 t \cos^3 q_1 t \\ &PQ^5 \cos p_1 t \cos^5 q_1 t \end{aligned} \quad (1)$$

The frequency determining quantities in 45 these terms are each in the form $\cos p_1 t \cos q_1 t$ or this quantity times one or more cosine squared quantities. Since $\cos^2 \alpha = \frac{1}{2} + \frac{1}{2} \cos 2\alpha$ the development of these quantities each contains one term of the form $\frac{1}{2} \cos p_1 t \cos q_1 t$. 50 This demonstrates that the terms of (1) each yields a pair of second order side bands. These side bands for the several terms are superposed to comprise resultant side bands.

The amplitude of each of the resultant upper and lower side bands may accordingly be 55 expressed as a series the terms of which are proportional to PQ , $P^3 Q$, $P^5 Q$, PQ^3 , PQ^5 , $P^3 Q^3$ —all being products of even order.

These terms will be multiplied by the coefficients $b, d, f, \dots$, of the general equation. In general these coefficients decrease in magnitude as the power of the terms of the general equation increases, that is, as the order of the above products increases. In 65 fact the characteristic curve may be caused

to be substantially "square" so that substantially only the term PQ , which is linear in Q , is present. For other cases the other terms will be present in relatively small amounts and will introduce some distortion on account of non-linearity of certain of the coefficients in Q . However, a number of the terms as PQ , $P^3 Q$, $P^5 Q$, etc., hence their sum, will be linear in Q . The magnitude of the distorting terms, that is, PQ^3 , PQ^5 , $P^3 Q^3$, etc., 70 may be minimized by making P large as compared with Q , so that substantial linearity may be obtained, as is necessary for distortionless transmission. This is true even though the characteristic curve departs widely from its "square" configuration. 80

It may be shown, in a manner similar to the above, that other side bands of a different even order may be obtained from other terms than those indicated in (1), in the expansion of the even power terms of the general equation. However, as will be more evident later, only those of the form $m p \pm q$ will have coefficients which are linear in Q and, therefore, useful. 85

From the odd power terms of the general equation odd order side bands may be similarly obtained. This will be demonstrated for the case of third order side bands.

From the expansion of these odd power terms (except the linear term) it will be found that alternate terms beginning with the second have even powers of $\cos p_1 t$ and odd powers of $\cos q_1 t$. These terms in their regular order, up to and including those for the seventh power term of the general equation, are as follows, retaining only the necessary coefficients. 95

$$\begin{aligned} &P^2 Q \cos^2 p_1 t \cos q_1 t \\ &P^4 Q \cos^4 p_1 t \cos q_1 t \\ &P^2 Q^3 \cos^2 p_1 t \cos^3 q_1 t \\ &P^6 Q \cos^6 p_1 t \cos q_1 t \\ &P^4 Q^3 \cos^4 p_1 t \cos^3 q_1 t \\ &P^2 Q^5 \cos^2 p_1 t \cos^5 q_1 t \end{aligned} \quad (2)$$

The frequency determining quantities in these terms are each of the form $\cos^2 p_1 t \cos q_1 t$ or this quantity times one or more cosine squared quantities. 105

Since $\cos^2 \alpha = \frac{1}{2} + \frac{1}{2} \cos 2\alpha$, the development of the portion $\cos^2 p_1 t \cos q_1 t$ contains the term $\frac{1}{2} \cos 2 p_1 t \cos q_1 t$. The product of this term with the development of the remaining cosine squared quantities results in a term made up of the product of this term and $\frac{1}{2}$. Accordingly, the development of each of the terms in (2) contains a term of the form $\cos 2 p_1 t \cos q_1 t$. This form is similar to the form $\cos p_1 t \cos q_1 t$ and in an analogous manner yields upper and lower side bands of $2p$. This demonstrates that the terms in (2) each denotes a pair of third order side bands of the type $2p \pm q$. 115

The amplitudes of each of the resultant upper and lower side bands may accordingly 120

be expressed as a series, the terms of which are proportional to P^2Q , P^4Q , P^6Q , P^2Q^3 , P^4Q^5 , P^2Q^5 . . . The sum of these terms is linear under the conditions discussed above 5 for second order modulation. That is, when there is only the third power term in the general equation, only the first term of the series occurs and the side bands are strictly linear in Q , and when there are additional terms, 10 there is a slight distortion which can be greatly minimized by properly proportioning the values of P and Q .

It may be shown in a similar manner that 15 third order side bands of the type $p \pm 2q$ may be obtained from other terms than those indicated under (2), of the development of the odd power terms of the general equation. The quantities expressing the amplitude of 20 these side bands are made up of terms none of which is linear in Q , so that the sum is not linear and cannot be made linear in Q . This means that third order modulation of 25 this type cannot yield a faithful reproduction of the signal. The same thing is true of other higher orders of modulation, even or odd, in which n is greater than one. These side bands may, however, be used in signaling where accurate reproduction of the modulating wave is not essential.

30 Side bands of a higher odd order than third of the type $m p \pm q$ can also be obtained from the odd power terms of the general equation. These side bands, as well as the higher even order side bands of the same 35 type, can be made substantially linear in Q .

By the method employed above in considering high order modulation, it can be shown that high order demodulation of a modulated wave can yield the original modulating wave. For example, if a wave of 40 frequency p_1 and a third order side band or modulated wave having a frequency $2p_1 + q_1$, where p_1 is the original carrier frequency and q_1 is the original modulating frequency, be 45 jointly impressed on a wave distorting means such as, for instance, the third order magnetic modulator referred to above, there will result a side band of the wave p_1 , which will have a frequency $(2p_1 + q_1) - 2p_1$, and which 50 will be equivalent to the original modulating wave of the frequency q_1 .

Although telephone systems now in use depend upon second order modulation and demodulation, experience has shown that certain 55 higher orders, especially the third, are suitable for the production of side bands and for the reproduction of speech. As illustrating the practicability of using the higher orders of modulation it was recently found 60 that in an actual carrier current telephone system arranged for optimum second order modulation conditions and for transmission of the unmodulated carrier component, the amplitude of the third order side bands 65 could, by adjustments not affecting the con-

ditions of second order modulation, be made of the same order of magnitude as that of the second.

It is apparent that the term "carrier frequency" must be re-defined for use in describing systems of modulation of higher order than the second. For example, a third order side band having frequencies $2p \pm q$, can be demodulated to reproduce a signal by either second or third order demodulation, 70 depending upon whether a current of frequency $2p$ or p is available. Accordingly, depending on the order of demodulation, either of these two frequencies may play the role played by the carrier frequency in a 75 system using second order modulation (and accordingly second order demodulation). In this specification the terms "carrier current" and "carrier wave" will be applied to any current or wave that may be combined in a distorting device with the transmitted side band or side bands to produce a signal, and the frequency of such current or wave will accordingly be designated a carrier frequency. A modulated wave of a high order may 80 accordingly have as carrier frequencies both the frequencies of the impressed high frequency wave and certain of its harmonics. The impressed high frequency wave will be 85 designated as the "impressed" "original" or "unmodulated" carrier wave.

Conditions favorable to the production of second order side bands are not necessarily favorable to the production of third order side bands or, generally, the conditions favorable to even order modulation are not necessarily favorable to odd order modulation, and vice versa. This is illustrated by Fig. 1 in which A and B are, respectively, the E_c — I_b characteristic curve and the curve 100 of the second order side band output current of a modulator recently tested. The modulator circuit was of the general type illustrated in U. S. patent to Van der Bijl, No. 1,350,752, issued August 24, 1920. A tungsten filament carrying a current of 1.35 amperes was used. The plate potential was 220 volts. The important thing is that when the grid is given a polarizing potential of -18 volts, the second order side band becomes substantially zero. This value of grid potential marks a point of symmetry of the characteristic curve. This condition, which is unusual and difficult to obtain with oxide coated filaments, was made possible by reason 105 of the choice of filament material and the critical values of the constants used. The other even order side bands would also be found to be substantially zero if modulation occurred about the same point. Although 110 the odd order side band output is not shown in the curve, it is not a minimum at that point.

The experiment demonstrates that if a characteristic curve having symmetry about 115

a point is represented by a power series, this series will have no even power terms, that is, the coefficients b , d , f , etc., of the general equation will each have zero values.

5 Although it is not necessary, in order to produce odd order side bands, to operate about a point of symmetry, such method of operation makes possible odd order modulation with suppression of even harmonics of the 10 impressed carrier frequency and with suppression of even order side bands since these components result from the terms in the general equation having the same exponents as the numbers indicating the frequency multiple. This expedient is of value, in its economy of energy, in the avoidance of interference due to the presence at the receiver of even order side bands, and on account of its 15 secrecy. Such a system is relatively secret, 20 since it insures that a would-be interceptor cannot readily detect the signal by second order demodulation between the odd order side bands and the appropriate even multiple frequency carrier. In multiplex communication 25 systems using side bands of different orders for the respective channels (an example of which is illustrated in Fig. 3 and which will be described later) the expedient insures a greater separation between message 30 carrying side bands.

Economy and secrecy are promoted in odd order modulation by complete carrier suppression, that is, by suppressing the impressed carrier as well as its even harmonics. 35 This may be accomplished, for example, by suppressing the even harmonics as above, and suppressing the impressed carrier by means of a filter. Since the odd order side bands are far removed in the frequency range 40 from the impressed carrier, separation can easily be effected by the filter. Suppression of the carrier frequencies may be accomplished in this simple manner without resort to balanced arrangement of tubes. This is 45 of importance in instances where, in the alternative that the usual second order modulating methods were attempted to be used with carrier suppression, the carrier frequency would be too high to permit separation 50 from the second order side bands without resort to such balanced arrangements. The method in which modulation is effected by varying the inductance of a coil by correspondingly variably saturating its magnetic 55 core, is especially applicable to suppressed carrier, odd order, modulation. Fig. 3 illustrates one modulating arrangement of this kind and also a system in which it, or any equivalent means, may be used.

60 Each of the specific frequency values mentioned hereinafter is merely an example of various values which may be employed in a system of the type shown.

In the system of Fig. 3 there are three two-way carrier telephone channels for telephonic

communication over a carrier line ML. Of the entire system only one carrier terminal station is shown, since the remainder of the system may be a duplicate of the station and connections indicated in Fig. 3 with a slight 70 exception pointed out hereinafter with regard to the source of supply of carrier current at the two stations.

The carrier line ML is associated for transmission purposes with low frequency or telephone lines L_1 and L_2 , through a modulating and demodulating channel 1 and a modulating and demodulating channel 2, respectively. For the purpose of transmission to the carrier line a transmitting and modulating channel TL_3 , including a telephone transmitter T and a second order magnetic modulator 5, is associated with line ML, through a two-way channel 3; and for the purpose of receiving from the carrier line a receiving and demodulating channel RL_3 including a receiver-demodulator 6 is associated with the carrier line, through the channel 3. A balanced three winding transformer or hybrid coil and an impedance balancing network 8 80 connect the channels TL_3 and RL_3 to a band filter 31 and in conjugate relation to each other, the filter 31 being interposed between the hybrid coil and the carrier line. The network 8 balances the impedance facing the hybrid coil at the line terminals of the hybrid coil, for frequencies in the neighborhood of the carrier and side band frequencies employed in the modulator 5 and the demodulator 6. The receiver-demodulator employs 85 second order demodulation.

The channel 1 comprises a low pass filter 10 and a band filter 11, a third order magnetic modulator and demodulator 12, a condenser 13 having low impedance for essential speech frequencies, and the output side of a carrier filter 14 through which carrier current is supplied to modulator and demodulator 12 by an oscillator 15 in cooperation with a harmonic generator 16 and a harmonic amplifier 17. 100 The oscillator, harmonic generator and harmonic amplifier may be of the type usual in carrier current telephone systems. For example, their structure and operation may be as disclosed in the paper by Colpitts and Blackwell on Carrier Current Telephony and Telegraphy, Journal of the A. I. E. E., vol. 40, page 205. The filters referred to herein may be of appropriate types disclosed in U. S. patent to Campbell, 1,227,113, May 22, 1917. 115

The modulator 12, which functions also as a demodulator for channel 1, consists of a toroidal magnetic core wound with a single coil. The function of the modulator is to distort the currents flowing through the coil so that third order side bands, one or both for transmission through filter 11 to line ML, are produced when carrier current is supplied to the modulator through filter 14 and 125 130

telephonic current is supplied to the modulator, from line L_1 , through filter 10, and so that speech currents are produced when carrier current of the frequency passed by filter 14 is supplied to the modulator through filter 14 and a third order speech side band of a carrier current of the pass frequency of filter 14 is supplied to the modulator, from the carrier line, through filter 11.

10 In channel 1 and line ML , the carrier frequency and the order of modulation or demodulation employed are the same for telephonic transmission in one direction in line L_1 as for telephonic transmission in the opposite direction in line L_1 . The frequency of oscillator 15 may be 5000 cycles per second. The harmonic generator 16 delivers harmonics of this frequency, and the frequency delivered by harmonic amplifier 17 and filter 14 15 may be 10,000 cycles per second. Filter 10 may pass frequencies from 0 to 3000 cycles. The telephonic signals to and from line L_1 may be transmitted over line ML on, say, an upper side band. This will be a third order side band, which will cover the range 20,000 to 23,000 cycles since the modulation employed for this channel is third order modulation. The filter 11 may pass this latter frequency range. It will suppress the 25 carrier frequency of 10,000 cycles. The modulator 12, when operating normally for telephonic transmission, will suppress even order side bands and will also suppress even harmonics of the impressed carrier frequency, including the first even harmonic.

What is believed to be the mode of operation of modulator 12 will now be explained by reference to Fig. 2. The curves f and g in this figure are the familiar $B-H$, or magnetization curves which express the relation 30 between the magnetizing force H and magnetic induction B . Curve f is the magnetization curve for positive variations of H which would be obtained if a magnetic core, as, for 35 example, the toroidal core in the magnetic modulator, having no initial residual magnetization, were variably magnetized by positive values of current. The curve g would be similarly obtained if negative values of 40 magnetomotive force were used. Curves f and g , taken together, exhibit perfect symmetry about the origin. The permeability of the core is measured by the ratio of B and H , that is, by the slope of the chords of the 45 magnetization curve between the origin and the reference points. The curves which express the absolute values of permeability corresponding to curves f and g have approximately the shape respectively of curves h and i , which obviously must be symmetrical about the axis of ordinates. Since the permeability is a factor in the equation which expresses the inductance of the magnetizing winding, the inductance varies in accordance with these 50 curves h and i . If the variable saturation of

the toroidal core with variable positive and negative values of impressed potentials is assumed to follow these curves h and i , the characteristic curve between the impressed potentials and current flowing through the 55 coil would be obtained by dividing these positive and negative values of impressed potentials by the ordinates of h and i . The resultant characteristic curve would correspond, for example, to the characteristic 60 curve A of Fig. 1, and would determine the modulating properties of the circuit. The curve would obviously have symmetry of the same type as that of curve f g , that is, it will have symmetry about a point. Accordingly, under the assumed conditions odd 65 order modulation would be achieved with suppression of the even order side bands and of even power harmonics of the impressed carrier frequency. This result is 70 achieved without the use of a polarizing means.

As a practical matter, the variation of B under conditions assumed above of variable H would, starting at the top of the positive 75 magnetization curve, follow the familiar hysteresis loop j , k , l , m , in which the ascending and descending branches m and k , and correspondingly the branches j and l , are 80 symmetrical with each other. Although the presence of residual magnetization affects the shape of the corresponding permeability 85 curves, they are, as a matter of fact, of the same general form as h and i , and the symmetry of the loop insures that these permeability 90 curves are symmetrical. Accordingly, the operation of the magnetic core modulator, even when there is hysteresis, 95 has the desirable features of odd order modulation with suppression of the even order 100 effects.

Of course, the hysteresis loop disclosed 105 would result only if the magnetizing current has not more than one maximum and minimum per cycle, as for example, a sine 110 wave current. In the actual case the magnetizing current consists of superposed carrier and modulating current, and the resulting wave form accordingly has numerous irregularities and reversals of slope. For this 115 case the hysteresis loop disclosed illustrates, for example, only the uniformly recurrent loop corresponding to the carrier current. The irregularities due to the modulating current would properly be shown as both large 120 and small hysteresis loops having their origins in the loop disclosed.

It is desirable to use a core which saturates at a small value of magnetizing current 125 so that the characteristic curve has pronounced bends at its two extremes, and accordingly so that there are more pronounced high order modulation effects. From another point of view, the use of a saturated core makes possible the production 130

of high order effects with the small values of impressed potential that for practical reasons must often be used.

Although in the above the effect of variation of inductance has been described, the corresponding variation of effective resistance contributes, although usually to a smaller extent, to the result, so that the effect may be considered broadly as a variation of impedance.

In practice, it has been found that the use of an alloy metal known as "Permalloy" for the core markedly improves the operation of the device. This metal is an alloy containing two elements of the magnetic group, such group being made up of manganese, iron, cobalt, nickel and copper. In its usual form the metal is an alloy of nickel and iron. Whatever its specific composition, it is distinguished by its pronounced magnetic properties and especially the remarkably low value of magnetomotive force required to produce saturation. These magnetic properties depend largely on the special heat treatment which is given to the alloy during its process of manufacture. Reference is made to a paper by Arnold and Elmen in the Journal of the Franklin Institute for May, 1923, and to U. S. patents to G. W. Elmen, Nos. 1,586,883 and 1,586,884, June 1, 1926, for descriptions of this alloy and its properties.

The channel 2 in Fig. 3 comprises a low pass filter 20, a band pass filter 21 and a third order magnetic modulator and demodulator 22 which employs cross magnetization in its toroidal magnetic core 23 corresponding to the toroidal core of modulator 12 but is otherwise similar to the modulator 12. Core 23 has a winding 24 corresponding to the winding of modulator 12, but only the modulating waves from line L_2 and filter 20, or in the case of demodulation a side band passed from the carrier line through filter 21, is applied to this winding, the carrier current being applied to a winding 25 on a magnetic yoke 26 shown with salient poles arranged in close proximity to core 23 to send flux through the latter core at right angles to the flux due to winding 24. Carrier current having a frequency of, say, 20,000 cycles per second is supplied to modulator 22, for use in modulation or demodulation, from the oscillator 15, harmonic generator 16 and a harmonic amplifier 27, the amplifier 27 selecting and amplifying the 20,000 cycle frequency component of the wave delivered by harmonic generator 16 and applying the amplified wave to winding 25.

The function of modulator 22 is to generate third order side bands, one for transmission through filter 21 to line ML, when carrier current is supplied to the winding 25 from amplifier 27 and telephonic current is supplied to the winding 24 from line L_1 through filter 20, and to generate speech frequency waves when carrier current of 20,000 cycles

per second is supplied to the modulator from amplifier 27 and a third order speech side band of a carrier current of 20,000 cycles is supplied to the modulator, from the carrier line, through filter 21. In channel 2 the carrier frequency and the order of modulation or demodulation employed are the same for telephonic transmission in one direction over line L_2 as for telephonic transmission in the opposite direction in line L_2 . Filter 20 may pass frequencies from 0 to 3,000 cycles. The telephonic signals to and from line L_2 may be transmitted over line ML on, say, an upper side band. This will be a third order side band, which will cover the range 40,000 to 43,000 cycles since the modulation employed for this channel is third order modulation. The filter 21 may pass the latter frequency range. It will suppress the carrier frequency of 20,000 cycles. The modulator 22 will suppress even order side bands and will also suppress even harmonics of the impressed carrier frequency, including the first even harmonic.

The magnetic coil modulator 12 illustrates what may appropriately be denoted longitudinal magnetization, since the fluxes resulting from the two magnetomotive forces follow parallel, that is, the same paths. It has been found that a similar effect is produced by what may be called cross-magnetization in which the windings are so arranged as for example in the manner illustrated in modulator 22, that the two fluxes tend to be normal to each other. The three circuits for the modulating, carrier and side band currents may be otherwise related as in the case of the modulator 12, or in any suitable manner. The use of cross magnetization has the advantage that undesired mutual inductance between the circuits for impressing waves on the modulator or demodulator can be made substantially zero, thereby avoiding the necessity of the use of means, for example, filtering means, for preventing undesired reaction between these circuits. In this connection it is noted that the filters 10 and 14, associated with line L_1 and amplifier 17, respectively, prevent either line L_1 or amplifier 17 from delivering current to the other; and that no carrier filter corresponding to carrier filter 14 associated with modulator 12 is associated with modulator 22. The effect of cross magnetization on the permeability, as well as physical structures for accomplishing cross magnetization are described in an article by Goldschmidt in the Elektrotechnische Zeitschrift for March 3, 1910, page 218.

Carrier current of say 10,000 cycles per second is supplied to modulator 5 and demodulator 6 from elements 15 and 16 and a harmonic amplifier 37, through carrier filter 34, channel 3 and hybrid coil 7. A low pass filter 30', having a pass range of say 0 to 3,000 cycles is interposed between transmitter

T and modulator 5. Telephonic signals to demodulator 6 and from modulator 5 may be transmitted over line ML on, say, an upper side band of the 10,000 cycle carrier. This 5 will be a second order side band, with a range of 10,000 to 13,000 cycles. Filter 31 will pass this range.

The station at the distant end (not shown) of line ML may be a duplicate of the station 10 shown, except that the oscillations for the harmonic generator at the distant station, corresponding to harmonic generator 16, are supplied from the oscillator 15 located at the station shown, through a base frequency amplifier 57, a base frequency filter 51 and the carrier line ML. The base frequency amplifier selects a wave of 5,000 cycles from element 16, amplifies the wave and transmits it through the 5,000 cycle filter 51.

20 A relay 60 is selectively responsive to ringing current, of say 16 cycles, from line L_1 , to effectively open the circuit of a relay 61 and thereby cause a battery 62 or other source of direct current to send current through modulator 12, a choke coil 63 which has high impedance for speech and carrier frequencies, and left hand contact of relay 61. This current subjects the core of the modulator to a unidirectional magnetomotive force for the 25 duration of the ringing current. The resulting biasing flux or unidirectional flux in the modulator core which is also subjected to the magnetomotive force due to the carrier current, causes the modulator to shift its operating point on its characteristic curve to a point other than that about which the curve is symmetrical, and consequently the modulator delivers a pronounced first even harmonic of the carrier frequency 10,000. This 30,000 30 cycle wave passes through the band filter 11, and over the carrier line, and through the corresponding band filter at the distant carrier terminal, and there operates, in a manner which will now be explained by reference to 40 the station shown, to send a ringing current over the low frequency telephone line terminating at the station.

When a wave of 20,000 cycles is received from the carrier line by filter 11, the wave is 50 transmitted to a magnetizing coil or winding 65 of a relay-demodulator 66, the coil 65 being connected in parallel with condenser 13 and the coil of modulator 12 by a circuit which extends through the normally closed right 55 hand contact of relay 61 and through two parallel branch circuits 67 and 68. The branch 67 contains a phase changer 70 between narrow band filters 71 and 72 which pass the frequency 20,000 cycles. The branch 68 contains a narrow band filter 73 which passes the frequency 10,000 cycles received from harmonic amplifier 17 through carrier filter 14. The relay-demodulator is a relay comprising a magnetic core 75, energized by 65 the winding 65, and an armature 76. In the

core 75 demodulation of third order takes place between the 10,000 and 20,000 cycle waves applied to winding 65. If the two waves be in proper phase relation, one of the demodulation products is a term proportional to $\cos^2 pt \cos 2 pt$, where p is 2π times the frequency 10,000. Therefore, since

$$\cos^2 pt = \frac{1}{2} + \frac{1}{2} \cos 2 pt,$$

it follows that there is a unidirectional flux produced in the relay core, though there is 75 no direct current in the relay winding. This unidirectional flux causes the armature 76 to close its contact and thereby energize a relay 77 which connects a source 78 of 16 cycle ringing current to line L_1 . By 80 having the circuit of winding 65 pass through the front contact of relay 61, it is insured that this circuit will be open whenever modulator 12 is generating a 20,000 cycle wave due to application of the voltage of battery 62 to the modulator 12. The armature of relay 66 should be unresponsive to alternating flux, and particularly to high frequency flux. The mention above of the proper phasing, which may be accomplished by varying the setting 90 of the phase changer until a sufficient force for operating the relay armature is obtained, has reference to the fact that at a certain phase angle α between the 10,000 and 20,000 cycle currents sent through winding 65, there 95 will be no unidirectional flux produced in the core 75. For example, if the currents be proportional to $\cos(pt + \alpha)$ and $\cos 2 pt$, respectively, where p is 2π times the frequency 10,000, then the constant term which yields 100 the unidirectional flux will be proportional to the $\cos$ of 2α , which vanishes when α is 45° and is maximum when α is zero.

The receiver-demodulator 6 comprises a closed magnetic path or core 80, having thereon windings 81 and 82 for energization by side band current delivered from filter 31 and windings 83 and 84 for energization by a direct current source 85. The receiver-demodulator also comprises magnetic polar projections 86 and 87 protruding from the core 80 at points 88 and 89 respectively and a magnetic sound reproducing diaphragm 90 mounted for vibration by the flux from the polar projections 86 and 87. The windings 81 and 82 have the same number of turns and are at opposite sides of the point 88 and are connected in series aiding relation, with respect to the closed flux path 80. The winding 83 has the same number of turns as winding 84, and is on the opposite side of point 89, and these two-windings are in series opposing relation, with respect to the closed flux path 80. The core 80 is symmetrical about a plane passing through points 88 and 89 at right angles to the plane of the closed magnetic path, and such a plane may be regarded as dividing the core or path into two halves, the reluctances of which are equal. Point 88 is at the same magnetic po- 110 115 120 125 130

tential as point 89, as regards carrier and side band magnetomotive force produced by windings 81 and 82, and therefore no fluxes of the carrier and side band frequencies flow through the projections 86 and 87. Winding 83 sends a unidirectional flux through the upper half of core 80, in one direction around the core 80, and winding 84 sends an equal unidirectional flux through the lower half of core 80, in the opposite direction around the core. These two fluxes return in the same direction through the path consisting of the projections 86 and 87, the diaphragm 90 and the air-gap between the diaphragm and the free poles of the projections.

The second order intermodulation of the impressed carrier and side band fluxes produces in each half of the closed magnetic path or core 80 a signal frequency flux which in magnitude and sign is dependent upon the algebraic product of the magnitudes of the carrier frequency flux, the impressed side band flux and the direct current flux. Since the direct current fluxes are of opposite sign or direction in the two halves of the core, the two algebraic products or signal fluxes of equal magnitude have opposite directions in the core. Therefore they flow in the same direction through the path consisting of the projections 86 and 87, the diaphragm 90 and the air gap at the diaphragm, and consequently cooperate with the direct current flux through the air gap to exert upon the diaphragm a vibromotive force substantially proportional to the product of the direct current flux and the signal flux resulting from demodulation.

In the operation of the system of which Fig. 3 forms one of two similar carrier terminal stations the channels 1, 2 and 3 provide for three two-way transmissions of telephone messages simultaneously over the carrier line, the transmissions between the carrier line and the lines L_1 and L_2 , respectively, employing third order modulation, and the transmission from the telephone transmitter T to the carrier line employing second order demodulation as does also the transmission from the carrier line to the telephone receiver 6. In each of the channels 1, 2 and 3 the carrier frequency is the same for one direction of transmission as for the opposite direction. For transmitting ringing signals from line L_1 to the carrier line, ringing responsive relay 60 causes a biasing magnetomotive force to be applied to the modulator 12, so that the modulator sends a wave of double the impressed carrier frequency to the carrier line. For transmitting ringing signals from the carrier line to line L_1 the relay-demodulator 66 responds to the double carrier frequency wave representing the ringing signal, and causes a 16 cycle generator to be connected to line

L_1 . The transmission of ringing signals to and from line L_1 does not interfere in any material degree with the telephonic transmission which may be simultaneously taking place in channels 2 and 3.

What is claimed is:

1. The method which comprises transmitting a signaling side frequency of a carrier wave with suppression of the carrier wave, and transmitting a second signal, other than that employing said side frequency, by re-introduction of said carrier wave.

2. The method which comprises generating a flux by intermodulating magnetomotive forces, and controlling a flux responsive mechanical device in response to the generated flux.

3. The method which comprises producing a flux having a unidirectional component by application of alternating magnetomotive forces to a magnetic path, and applying said flux to a device selectively responsive to said unidirectional component of said flux.

4. A signaling system comprising an odd order modulator, means for impressing a carrier wave and a modulating wave on said modulator, means for causing said modulator to generate an even harmonic frequency of said impressed carrier wave, a carrier line for transmitting a side frequency wave generated by said modulator in response to said carrier and modulating waves, an electromagnetic relay, connections for transmitting said side frequency wave from said modulator to said carrier line and for transmitting waves of the frequency of said harmonic from said carrier line to said relay, and means for supplying to said relay waves of the frequency of said carrier wave.

5. A system in accordance with claim 4, comprising a telephone line in said means for impressing said carrier and modulating waves on said modulator, and comprising a relay responsive to ringing current from said telephone line for controlling said connections, a source of ringing current and means controlled by said electromagnetic relay for connecting said source to said telephone line.

6. A communication system comprising a plurality of two-way multiplexed carrier telephone channels, a carrier line for said channels, third order magnetic modulating and demodulating means for one of said channels at each terminal of said carrier line, second order magnetic modulating and demodulating means for a second of said channels at each terminal of said carrier line, means for supplying to each of said modulating and demodulating means a carrier frequency for demodulation and the same frequency for modulation, said carrier frequency being the same for said third order as for said second order modulating and demodulating means, means responsive to ringing current at one terminal of said carrier line

for magnetically biasing one of said third order modulating means to cause it to generate the first even harmonic of the carrier frequency impressed thereon, a ringing current generator at the distant terminal of the carrier line, and means at said distant terminal responsive to said harmonic to control said ringing current generator.

7. A signaling system comprising means 10 for generating and transmitting a side frequency of a carrier wave with suppression of the carrier wave, and means for reintroducing said carrier wave to convey a signal other than that identified by said side frequency.

8. The method which comprises transmitting a signaling side frequency of a carrier wave with suppression of the carrier wave, and transmitting a ringing signal by transmission of a harmonic of said carrier wave.

9. The method of signaling, employing an odd order modulator which comprises transmitting a signaling side frequency of a carrier wave with suppression of the carrier wave, and biasing said modulator to transmit a signal other than that employing said side frequency.

10. A signaling system comprising an odd order modulator, means for impressing a carrier wave and a modulating wave on said modulator, means for transmitting a side frequency generated by said modulator, means for biasing said modulator causing it to generate a harmonic of said carrier wave, and means for utilizing said harmonic wave for transmitting a signal other than that employing said side frequency.

11. The method which comprises generating an alternating flux by distorting superimposed magnetomotive forces and controlling a flux responsive sound producing device in response to the generated flux.

12. A combined telephone receiver and demodulator comprising means responsive to carrier and modulated currents for producing carrier and modulated magnetomotive forces, means for demodulating said magnetomotive forces to produce a demodulated signal flux and vibratory sound producing means operable in response to said flux.

13. The method of producing a signaling wave which comprises subjecting a magnetic path to magnetomotive forces which are substantially at right angles to each other throughout said path and the magnitude of one of which is a function of the magnitude of a signaling wave and the magnitude of the other of which is a function of the magnitude 60 of another wave whereby a magnetic flux is generated and controlling a flux responsive mechanical device in response to the generated flux.

14. The method which comprises jointly 65 impressing on a magnetic path a carrier wave

of magnetomotive force and a signaling wave of magnetomotive force at right angles to said carrier wave and utilizing the resultant flux comprising side bands of higher order to control a flux responsive mechanical device.

15. The combination with an electromagnet having a magnetic core with a gap therein of an electromagnet in said gap, a winding included in the second mentioned electromagnet for creating flux lines in a plane at right angles to the flux in said gap due to said first electromagnet whereby a resultant flux is generated and a flux responsive mechanical device controlled in response to the resultant flux.

In witness whereof, I hereunto subscribe my name this 29th day of October, A. D. 1926.

EUGENE PETERSON.
